UNITED STATES PATENT OFFICE.

PHILIPP HUMMEL, OF STRASSBURG, GERMANY, ASSIGNOR TO MATHILDE HUMMEL, OF STRASSBURG, GERMANY.

CONVEYER-BAND FOR CIGARETTE-MAKING MACHINES.

No. 814,908.

Specification of Letters Patent.

Patented March 13, 1906.

Application filed August 10, 1905. Serial No. 273,672.

To all whom it may concern:

Be it known that I, PHILIPP HUMMEL, a subject of the German Emperor, residing at Strassburg, Germany, have invented certain new and useful Improvements in Conveyer Bands for Cigarette - Making Machines, of which the following is a specification.

The present invention relates to an improved conveyer - band such as is used in machines for making cigarettes; and the object of the invention is to provide such a band or strap which embodies durability, imperviousness, and cheapness.

In order to make this invention more readily understood, I will now describe it with reference to the accompanying drawings, in which—

The band is composed of a soft-rubber or the like pliable core or filling a and the fabric proper, b. The latter is so placed about the rubber insertion that the edges meet along the longitudinal middle line, as is clearly shown in Figs. 1 and 2. The edges are then sewed together, preferably by means of an undulatory or meandering seam alternately crossing the middle line. The adhesive property of the rubber insertion and the seam c combine to make a tight joint between the linen folds. Such a band has the great advantage that its edges are not liable to fray and that the rubber or the like filling renders it absolutely impervious.

What I claim, and desire to secure by Letters Patent of the United States, is—

A conveyer-band for cigarette-machines, comprising in combination, a rubber or the like pliable filling, and a fabric envelop, the meeting edges of which are united by means of an undulous seam, approximately along the longitudinal middle line of the band, substantially as and for the purpose set forth.

In testimony whereof I affix my signature in presence of two witnesses.

PHILIPP HUMMEL.
